LASTING MACHINE

Ernest L. Butler and Andrew Eppler, Jr., Lynn,
Mass., assignors to United Shoe Machinery
Corporation, Flemington, N. J., a corporation
of New Jersey

Application May 27, 1949, Serial No. 95,598

25 Claims. (Cl. 12—10)

1

This invention relates to a machine for lasting different portions of the upper of a shoe, successively, in different locations along the edge of the shoe bottom in which the lasting margin of the upper is secured in lasted position, in each location, by means of an adhesive and is herein illustrated as embodied in a machine of the type disclosed in United States Letters Patent No. 1,796,451, issued on March 17, 1931, in the name of George Goddu. It will be understood, however, that in certain aspects the invention is not limited either to use for lasting with an adhesive or to embodiment in a machine organization of the exact construction disclosed in the aforementioned patent.

In lasting different portions of the upper of a shoe, successively, as for example by means of the gripper of a machine of the type referred to above, it is desirable that the gripper engage the different portions of the upper materials, hereinafter called the upper, in locations not too widely spaced apart, in a direction lengthwise of the shoe, to the end that substantially all portions of the upper will be subjected to the lasting stress, applied by the gripper, and stretched snugly over the last. However, after the upper has been stressed, in one location, and its lasting margin secured to the bottom of the shoe in that location, through the action of an overlaying member, either by an adhesive or other type of fastening, for example, a staple, the lasting margin curves in a direction lengthwise of the shoe from the position where it lies flatly against the shoe bottom to a position where it extends upwardly away from the bottom of the shoe. Inasmuch as the gripper, after it has stressed one portion of the upper, opens and then moves in a direction to carry the jaw which engages the inside surface of the upper downwardly and outwardly toward the edge of the shoe bottom, the shoe must be displaced a considerable distance, in a lengthwise direction, in order that this inner jaw may get in under the curved portion of the lasting margin of the upper. Also, if the gripper seizes the lasting margin of the upper closely adjacent to the location where it has been secured to the bottom of the shoe, there will be a tendency for the gripper, when it moves in a direction to tension the upper, to lift up that portion of the upper which has just been secured to the shoe bottom. Where the upper has been secured to the shoe bottom by means of a staple, the staple may be pulled out or, if secured by an adhesive, the adhesive bond may be broken. Accordingly, in the use of lasting machines of the

2

type disclosed in the aforementioned patent, it is necessary for the operator, who supports and feeds the shoe manually, to exercise a certain amount of care and discretion in moving the shoe between successive actions of the gripper and overlaying member so that different portions of the upper will certainly be engaged by the gripper and in such locations as not to disturb portions of the upper which have previously been secured to the shoe bottom.

It is an object of this invention to provide novel and improved means for so operating the gripper of a lasting machine as to make it possible for the gripper to engage different portions of the lasting margin of the upper of a shoe in closely spaced locations and to tension the upper in these locations without disturbing adjacent portions of the upper which have been previously secured in lasted position to the bottom of the shoe by an overlaying member. With this end in view, and in accordance with a feature of this invention, there is provided in a lasting machine having a gripper and an overlaying member, operable in time relation, the combination with mechanism for operating the gripper to seize, tension and release portions of the upper of a shoe, successively, in different locations along the edge of the shoe bottom, of mechanism for oscillating the gripper lengthwise of the shoe, away from and then toward a position in line with the overlaying member, after the gripper has tensioned and released one portion of the upper and prior to tensioning another portion of the upper.

More particularly, the arrangement is such that the gripper may be selectively oscillated in either direction, lengthwise of the shoe and relatively to the overlaying member, so that a shoe may be lasted in either direction, from toe to heel or heel to toe, and, in accordance with another feature of the invention, the gripper-operating mechanism and the gripper oscillating mechanism may be so relatively timed as to cause the gripper, when moving toward a position in line with the overlaying member, to seize a portion of the upper which is offset from the overlaying member and to displace this portion in a direction lengthwise of the shoe and into alignment with the overlaying member, prior to its operation for tensioning this other portion of the upper. Preferably, the gripper-operating mechanism is also arranged to move the gripper downwardly and laterally of the shoe, in time relation to the action of the gripper-oscillating mechanism. Because of the movements which are imparted to the gripper by the actions of the gripper-operat-

ing and the gripper-oscillating mechanisms, when the shoe is displaced in a lengthwise direction, to present another portion of the upper to the actions of the gripper and the overlaying member, the jaw of the gripper which engages the inner surface of the upper is first advanced toward the upper in a location where the upper extends away from the shoe bottom and is then moved in a direction lengthwise of the shoe and toward a position substantially in line with the overlaying member, before the gripper is operated to seize and tension this other portion of the upper. Thus the gripper jaw is readily inserted beneath the lasting margin of the upper closely adjacent to a location where the lasting margin has been secured to the shoe bottom. Also, by causing the gripper to seize a portion of the upper which is offset from the overlaying member and to displace this portion in a direction lengthwise of the shoe, a certain amount of fullness is placed in that portion of the lasting margin between the gripper and the location where the upper has been secured to the shoe bottom. Hence, when the gripper is operated to tension another portion of the upper, this fullness which has been secured to the shoe bottom.

Although the aforementioned advantages of the novel and improved gripper-operating mechanism may be obtained when the shoe is manually fed along by the operator, by increments of a magnitude such as to cause the gripper and overlaying member to operate, successively, on closely spaced portions of the upper, in accordance with another feature of the invention, means are provided for intermittently feeding the shoe to present different portions of the upper to the actions of the gripper and the overlaying member. Preferably, and as herein illustrated, this feeding means comprises a feed wheel for engaging the bottom of the shoe and arranged, selectively, to feed the shoe in either direction. The feeding means is also arranged to feed the shoe in the opposite direction, when the gripper is moving away from the overlaying member, and to hold the shoe against movement in the direction of feed when the gripper is moving toward a position in line with the overlaying member. In this manner, the feeding means acts also to hold the shoe stationary during that portion of the return movement of the gripper after the gripper has seized another portion of the upper and is displacing it in a direction lengthwise of the shoe.

Another object of this invention is to provide a novel overlaying member and improved means for operating the overlaying member, in time relation to the updraw and overdraw actions of the gripper. To this end, the overlaying member is arranged to move along a path that is inclined downwardly toward the bottom of a shoe presented to the machine and is provided with an operating surface that is disposed at an angle to its path of movement and substantially parallel to the bottom of the shoe, while the operating mechanism is arranged to cause the overlaying member first to move toward the shoe bottom, during a portion of the updrawing action of the gripper, then to pause while the updrawing action is completed and finally to continue its movement during the overdraw so as to lay the lasting margin of the upper in over, and to press it against the bottom of the shoe just as the upper

is released by the gripper. With this novel overlaying member construction, the lasting margin of the upper is laid flatly against the bottom of the shoe while the improved action of the means for operating the overlaying member not only insures that the updraw action of the gripper will be completed before the overlaying member engages the upper but also makes certain that the overlaying member will engage, and follow, the upper during the overdrawing action of the gripper so as to be in a position to press the lasting margin against the shoe bottom at the instant it is released by the gripper.

When lasting with an adhesive, it is necessary that the lasting margin be pressed firmly against the bottom of the shoe with a considerable force to insure that the lasting margin of the tensioned upper will be securely bonded to the shoe bottom. It is also desirable that this bonding pressure be applied to the entire lengthwise extent of the lasting margin without any gaps between locations where pressure is applied. Accordingly, and in accordance with another feature of the invention, the overlaying member is provided with a hammer which is adapted to strike the lasting margin a sharp blow, after the lasting margin has been pressed against the shoe bottom by the overlaying member. Preferably, this hammer is arranged so as to project through the operating surface of the overlaying member and is so mounted as to be self leveling to strike the lasting margin squarely and evenly, regardless of lengthwise and widthwise curvatures of the shoe bottom. Also, to the end that all portions of the lasting margin be subjected to the pressure of the overlaying member and/or the hammer, the feeding means is so constructed and arranged as to impart feeding movements to the shoe of a linear extent that is less than the width of the areas to which pressure is applied.

Other objects and features of this invention will appear in the following detailed description of the embodiment illustrated in the accompanying drawings and will be pointed out in the claims.

In the drawings,

Fig. 1 is a perspective view of a lasting machine embodying the features of this invention;

Fig. 2 is a view similar to that of Fig. 1 taken from the opposite side of the machine;

Fig. 3 is a view in side elevation showing the operating elements of the machine with certain parts broken away and others shown in section;

Fig. 4 is a view in section, substantially on line IV—IV of Fig. 3 and looking in the direction of the arrows, of certain of the operating elements;

Fig. 5 is a view of one of the operating elements of the machine as viewed from below and partly broken away;

Fig. 6 is a view in side elevation of operating mechanisms forming part of the machine shown in Figs. 1 and 2;

Fig. 7 is a view in section, substantially on line VII—VII of Fig. 6 and looking in the direction of the arrows, of a portion of one of the operating mechanisms shown in Fig. 6;

Fig. 8 is a view in side elevation of a part of the other operating mechanism shown in Fig. 6;

Fig. 9 is a view in side elevation of the operating elements of the machine similar to that of Fig. 3 but at a smaller scale and illustrating other operating mechanisms;

Fig. 10 is a view of an operating mechanism forming part of the machine shown in Figs. 1 and 2, with certain parts in vertical section;

Fig. 11 is a view in section, substantially on the line XI—XI in Fig. 10 and looking in the direction of the arrows;

Fig. 12 is a view in section substantially on line XII—XII in Fig. 10 and looking in the direction of the arrows;

Fig. 13 is a view in section, substantially on line XIII—XIII in Fig. 1 and looking in the direction of the arrows, of a detail of construction of the machine;

Fig. 14 is a view in detail of the construction of a portion of one of the operating mechanisms shown in Fig. 6, as viewed from the right-hand side of this figure;

Fig. 15 is a view in section of another detail of construction of the machine, substantially on line XV—XV in Fig. 9 and looking in the direction of the arrows;

Fig. 16 is a perspective view illustrating the action of one of the operating elements of the machine;

Figs. 17, 18 and 19 are views in side elevation showing different positions assumed by certain of the operating elements of the machine during an operating cycle; and

Fig. 20 is a timing chart.

Referring to the drawings and particularly Figs. 1 and 2 thereof, the features of this invention are illustrated as embodied in a machine of the same general construction as that shown in the aforementioned patent. This machine has a gripper, comprising jaws 30, 32, an overlaying member, indicated generally by the reference character 34, a shoe-bottom-engaging feed wheel 36, and an edge gage roll 38. These several operating elements are associated with, and operated by, mechanism contained within, a hollow head construction 40 which is mounted on the top of a column 42 of suitable height. The various operating mechanisms are driven from cams carried by a main shaft 44 which is driven from a power source not shown, by means of a clutch mechanism similar to that provided in the machine of the mentioned patent, and under the control of two treadle rods 46 and 48, corresponding respectively to the two treadle rods 126 and 184 of the patented machine.

Turning now to Figs. 1, 2, 6, 7, 13 and 14, the gripper is of the same construction as that of the prior patent and is suspended from a two-part updrawing lever 50, mounted on the head 40, by means of a pivot pin 52, Fig. 13, and its body portion 54 is slidably mounted in a member 56 that is threaded to receive a screw 58, Fig. 14, for a purpose to be explained below. The screw 58 is rotatably supported, at its opposite ends, in a bracket member 60 and an extension 62 secured thereto, and this bracket member is formed integrally with an overdraw rod 64, which corresponds to the overdraw rod 210 of the patented machine and is connected to a two-piece overdraw lever 66 by means of a pin 68 and block 70, Fig. 7. Carried by the updraw lever 50 is a gripper-closing rod 72 which, at certain times in the operating cycle of the machine, closes the jaws 30, 32 against the resistance of a jaw-opening spring 74, Fig. 1.

The gripper of the herein illustrated machine is operated in the same manner for seizing, updrawing, overdrawing and releasing different portions of the upper of a shoe as the gripper disclosed and described in the aforementioned patent, the gripper-closing rod 72, updraw lever 50, overdraw rod 64 and gripper-opening spring 74 being under the control of various operating

cams, not shown, carried by the main shaft 44. Also, the updraw action and overdraw action imparted to the gripper jaws 30, 32, by the updraw lever 50 and the overdraw rod 64 may be varied, respectively, by a hand nut 76 and a hand lever 78 in the same manner and by mechanisms similar to those disclosed in the aforementioned patent to which reference may be made for a detailed description of these various gripper-operating mechanisms which form no part of the present invention.

Referring again to the screw 58, which is received by the member 56, in which the body portion 54 of the gripper is mounted, this screw is adapted, when rotated, to impart additional movements to the gripper jaws 30, 32, for the purpose of certain features of this invention. In the operation of the gripper-operating mechanism which has been so far described, and as set forth in the prior patent, after the gripper has tensioned a portion of the upper of a shoe, the jaws 30, 32 are first opened, next moved downwardly to position the inner jaw 30 close to the bottom of the shoe, and then the gripper is moved laterally of the shoe to shift the inner jaw 30 outwardly to the edge of the shoe bottom and into a position to engage the inside surface of the upper material when the jaws are again closed. In addition to these movements of the gripper, which take place in a vertical plane substantially in line with the overlaying member 34, the gripper jaws 30, 32 are oscillated in a direction lengthwise of the shoe, first away from and then toward a position in line with the overlaying member, in the following manner.

The screw 58 has formed thereon a pinion 80 which meshes with a rack 82 that is slidably mounted in the bracket member 60 and connected, by means of a link 84, to an arm 86, Fig. 6. This arm is pivoted on a stud 88, carried by an upstanding portion 90 of the head 40 and has two oppositely extending ears 92, 94, to which are connected, respectively, links 96 and 98, Figs. 1 and 6. At its forward end, the link 96 is provided with an elongated slot 100, having at its inner end an upwardly offset portion 102, while the link 98 is similarly provided with an elongated slot 104 and a downwardly offset portion 106, Figs. 6 and 8. The ends of these two links are embraced by the bifurcated end of an arm 108 of a bell-crank lever, having another arm 110, that is mounted on a stud 112 carried by a downwardly extending portion 114 on the head 40. A pin 116 extends through the elongated slots in the ends of the links 96 and 98 and this pin is mounted in the bifurcated end of the arm 108.

The arm 110 of the bell-crank lever carries a cam roll 109, which engages a cam 111 on the main shaft 44 (Fig. 9) and this cam is so shaped that the bell-crank lever is rocked, once for each revolution of the main shaft, first down to the position shown in Fig. 6 and then up in the direction of the arrow. When the two links 96 and 98 are moved downwardly and to the positions shown in Fig. 6, the pin 116 will engage the offset portion 102 of the slot 100 in the link 96, while at the same time sliding freely along the slot 104 in the link 98, so that the link 96 will be reciprocated in such a manner as to cause the arm 86 to oscillate, down from the dotted line position to the solid line position shown in Fig. 6 and then back to the dotted line position. On the other hand, when the links 96, 98 are moved upwardly, the pin 116 will engage the offset por-

tion 106 of the slot 104 in the link 98 (see Fig. 8), while sliding freely along the slot 100 in the link 96, so that the link 98 will be reciprocated in such a manner as to cause the arm 86 to oscillate upwardly from, and back to, the dotted line position shown in Fig. 6. When the links 96 and 98 are moved downwardly, to the position shown in Fig. 6, the screw 58 will be rotated back and forth, through the actions of the rack 82 and the pinion 80, in such a manner as to cause the body portion 54 of the gripper to be swung about the axis of pin 52, Fig. 13, in a direction first to carry the jaws 30, 32 to the right, solid arrow in Fig. 14, away from a mid-position in which the jaws are substantially in line with the overlaying member 34, and then to return the jaws to mid-position. By elevating the links 96 and 98, the action of the screw 58 may be reversed so that the jaws are first carried to the left, dotted arrow in Fig. 14, away from the mid-position, and then returned to their mid-position.

For moving the links 96 and 98 to, and for holding them in, their up or down position, the following mechanism is provided, rods 120, 122 are pivoted, respectively, to the links 96 and 98, and each of these rods passes through an opening 124 formed in a block 126 that is carried by a hand lever 128, Fig. 6. For the purpose of simplicity, and since the lower end of the rearmost rod 122 is substantially hidden behind the lower end of the front rod 120, only the lower end of the latter is shown in the drawings. On each of these two rods there are a pair of collars 130 and 132 between which and the block 126 are mounted compression springs 134, 136. A tension spring 138 is stretched between the block 126 and a lip 140, supported on stud 112, and the arrangement is such that the spring 138 acts as a toggle spring for holding the hand lever in either position to which it may be shifted, either to elevate or to lower the links 96 and 98, through the actions of springs 134, 136. Thus, by manipulating the lever 128, the gripper jaws 30, 32 may be selectively oscillated in either direction lengthwise of the shoe first away from and then toward a position in line with the overlaying member. This oscillation of the gripper jaws 30, 32 in a direction lengthwise of the shoe is effected in a definite time relation to the operation of the gripper jaws to seize, updraw, overdraw and release a portion of the lasting margin of a shoe as will be more particularly explained below.

The overlaying member 34 is mounted for sliding movement on a guide block 150 which is secured to an arm 152, formed integrally with a trunnion shaft 154, Figs. 3 and 15. This trunnion shaft is journaled in a portion of the head 40 and has a reduced end portion 156 to which there is keyed an arm 158. This arm carries two adjusting screws 160, 162 which are adapted to bear against a stud 164, screwed to the head 40. By manipulating these screws, the guide block 150 may be tilted, relatively to the head 40, so as to vary the angularity of the path of movement of the overlaying member with relation to the bottom of a shoe presented to the machine. The overlaying member 34 is reciprocated on the guide block 150 and along a path inclined downwardly toward the bottom of the shoe, in time relation to the action of the gripper by means of a cam 170 on the main shaft 44 which engages a cam roll 172, carried by the overlaying member, see Fig. 9. The path of this cam is shaped with two risers 171, 173, so that the overlaying member is

5 moved toward the shoe bottom in two distinct steps.

For laying the lasting margin of the tensioned upper in over, and for pressing it against, the bottom of a shoe, the overlaying member is provided with an operating surface 180, having a nose 181, which is disposed at an angle to the path of movement of the overlaying member and in a plane that is substantially parallel to the bottom of a shoe presented to the machine, Figs. 3, 9, 17, 18 and 19. As shown in Fig. 19, when the overlaying member 34 is moved along its inclined path by the cam 170, the operating surface 180 will lay the lasting margin of the upper over, and press it flatly against, the bottom of the shoe. In order to augment the pressing action of the overlaying member, it is provided with a hammer 182 which is arranged to project through an opening 185 in the operating surface 180 and to strike the lasting margin of the upper a sharp blow after the lasting margin has been laid in over, and pressed against the shoe bottom, by the operating surface 180.

This hammer is carried at the lower end of a plunger 184 which is slidably mounted in the front end of the overlaying member 34, Figs. 3 and 9. At its upper end, this plunger is connected to an operating link 186 which is pivoted to a bell-crank lever 188, carrying a roll 190 that is held against a cam 192 by means of a spring 194, see Fig. 9. The cam 192 is mounted on the main shaft 44 and is so shaped that the plunger 184 will be projected downwardly by the spring 194, to cause the hammer 182 to strike the lasting margin a sharp blow, at the termination of the outward and downward movement of the overlaying member by the cam 170. An adjustable stop 193 is arranged so as to engage a bumper block 195, carried by the overlaying member, for limiting downward movement of the plunger 184. The hammer 182 is provided with an operating face having a plurality of projections 196, Fig. 5, so as to concentrate its action over a plurality of closely spaced points on the lasting margin and is mounted so as to be self leveling in the following manner. The lower end of the plunger 184 has a spherical recess 198 and the hammer is spherically shaped at 200 so as to be held in this recess by means of a spring 202, Figs. 3 and 19.

The shoe-bottom rest of the machine comprises a feed wheel 36 which is operated to move the shoe along in time relation to the actions of the gripper and overlaying member in the following manner (Figs. 1, 2, 3, 9 and 10). The feed wheel is formed integrally on the end of a shaft 298 that is journaled in the lower part of a forwardly and downwardly extending bracket 300 forming part of the head 40 (Figs. 3 and 10). On the shaft 298 is a bevel gear 302 which meshes with a bevel gear 304 carried by a shaft 306 that extends upwardly in the bracket 300. The shaft 306 is provided with a portion 308 of enlarged diameter which is received in a counterbore 309, formed in the bracket, and beyond the enlarged portion 308 there is pinned to the shaft 306 an elongated hub 310 which comprises part of a double-faced ratchet wheel 312, Fig. 10. Slidably mounted on the hub 310 and on an extension 314 of the shaft 306 is a cage 316 comprising end plates 318, 320 and a cylindrical intermediate member 322, secured together by means of screws 324, Fig. 10. The end plate 320 has 55 60 65 70 75 75 extending therefrom a shaft 326 which is jour-

naled in the bracket 300 and bored to receive the end 314 of the shaft 306.

Referring to Figs. 10 and 11, there is secured to the end plate 318 a sheet metal disc 328 which is cut away so as to provide three outwardly projecting spring fingers 330. The lower face of the ratchet wheel 312 is formed with a series of teeth 332 that are faced in a direction opposite to the fingers 330. Similarly, there is secured to the end plate 320 a disc 334 that is formed with three spring fingers 336 and the upperface of the ratchet wheel 312 is provided with a series of teeth 338 that face in a direction opposite to the fingers 336 and also opposite to the teeth 332. The shaft 326 is formed with a pinion 340 which is adapted to mesh with either one of two racks 342 or 344.

With the various parts in the positions shown in Fig. 10, when the rack 342 is moved rearwardly the ratchet wheel 312 will be driven by the fingers 330 so as to rotate the feed wheel 36 in a clockwise direction, see solid arrow, through the shaft 306 and the gears 302 and 304. However, when the rack 342 is moved reversely, rotation of the shaft 306, and hence of the feed wheel, is prevented by the engagement of a pair of spring fingers 346, secured to the bracket 300, with a notched surface 348 formed on the upper end of the enlargement 308 on the shaft 306, see Figs. 10 and 12. On the other hand, if the shaft 326 is moved downwardly so as to bring the pinion 340 into mesh with the rack 344, the fingers 336 will be brought into engagement with the teeth 338 and rearward movement of the rack 344 will effect rotation of the feed wheel in the opposite direction (dotted arrow). Upon reverse movement of the rack 344, the spring fingers 346 will hold the feed wheel 36 against rotation in the same manner as before.

The racks 342 and 344 are joined together for simultaneous reciprocation in the following manner. Connected to the inner ends of these two racks is a link 350, Figs. 2, 9 and 15, and this link is connected to a block 352 that is adjustably secured, by means of a clamping screw 354, in a groove 355 that is formed in an arm 356. This arm is rotatably mounted upon the end 156 of the shaft 154 and is held in place thereon by means of a plate 358. Formed integrally with the arm 356 is an extension carrying a roll 360 that engages a cam 362 carried by the main shaft 44. This cam is so shaped that the racks 342, 344 are reciprocated to the left as viewed in Fig. 9, once for every revolution of the main shaft and in time relation to the actions of the gripper and the overlaying member.

For shifting the position of the shaft 326, to bring the pinion 340 into engagement with one or the other of the racks 342 or 344, the following mechanism is provided. A grooved collar 366, secured to the upper end of the shaft 326, is engaged by rollers 368 carried by one end of a lever 370 that is pivotally mounted on a portion of the bracket 300, Figs. 2 and 10. Passing through a hole 372 formed in one end of the lever 370 is a rod 374 to which are secured two collars 376 and 378, Fig. 2, and between these two collars and the end of the lever 370 are compression springs 380, 382. A tension spring 384 is stretched between a pin 385, on the bracket 300, and another pin on the opposite end of the lever 370. This spring acts as a toggle spring and tends to hold the lever 370, and with it the shaft 326, in either one of two positions, namely, in the positions shown in Fig. 10 in which the pinion 340 is in

mesh with the rack 342 and the fingers 330 drive the ratchet wheel 312, or in a lowered position in which the shaft 326 is moved downwardly so that the pinion 340 meshes with the rack 344 and the ratchet wheel 312 is driven by the fingers 336, as explained above. The rod 374 is connected to one arm 390 of a bell-crank lever the other arm 391 of which is connected to the hand lever 128 by means of a rod 392, Figs. 1 and 6.

Referring to Figs. 6, 10 and 14, when the lever 128 is in the position shown in solid lines, Fig. 6, the gripper jaws 330, 332 will be oscillated in a direction lengthwise of the shoe, first away from and then toward a mid position in line with the overlaying member 34. In thus moving away from the mid position, the jaws will go to the right as viewed in Fig. 14. At the same time, the lever 370 will be swung to the position shown in Fig. 10 so that the feed wheel 36 will be rotated, in a clockwise direction, and a shoe held against the feed wheel moved to the left. On the other hand, when the hand lever 128 is moved down to the dotted line position in Fig. 6, solid line position in Fig. 1, the gripper jaws will move away from the mid position and to the left, as viewed in Fig. 14, and the feed wheel 36 will be rotated in a counterclockwise direction, Fig. 10, so as to feed a shoe in the opposite direction or to the right. In other words, and as will be explained below, by manipulating the hand lever 128, the direction in which the shoe is fed may be reversed and, at the same time, the direction in which the gripper jaws are moved away from their mid position is simultaneously reversed. Thus, in moving away from their mid position, the gripper jaws always travel in a direction opposite to that in which the shoe is being fed along by the feed wheel.

In order to make it possible for an operator to feed a shoe manually, mechanism is provided for freeing the feed wheel 36 so that it can rotate idly. This mechanism comprises a shaft 400 having a flattened side 402 that is in engagement with the lower face of the enlargement 308 and the shaft 306, Fig. 10. On the outer end of this shaft a knurled knob 404 is secured and beneath this knob a pin 406 passes through the shaft 400. A compression spring 408 is arranged so as to carry the shaft 400 to the left and upwardly, as viewed in Fig. 10, to hold the pin 406 in one or the other of two grooves 410 cut in the face of a boss 412 at right angles to each other. When the knob is pulled out to lift the pin 406 out of a groove 410, the shaft may be rotated to cause the flattened side 402 to lift the shaft 306, by engagement with the enlarged portion 308, thus disengaging the gears 304 and 302 and freeing the feed wheel 36.

The edge guide roll 38 is rotatably supported on the outer end of a supporting member 420 that is pivotally mounted on a stud 422, Fig. 3. This stud is carried by a block 424 which is adjustably secured to the head 40 by means of a clamping screw 426. The member 420 extends rearwardly beyond the stud 422 and is provided with an arcuate slot 428 through which there extends a binding screw 430 that is threaded into the block 424. By loosening the binding screw 430, the member 420 may be rocked about the axis of the stud 422 to elevate or lower the edge guide roll 38, while by loosening the clamping screw 426 the block 424 may be shifted on the head 40 to vary the lateral position of the edge guide roll.

The mode of operation of the several elements of the machine will now be explained with refer-

ence to the lasting of a shoe comprising an upper U and lining L assembled on a last A together with an inner sole I.

Referring particularly to Figs. 3, 4, 16, 17, 18, 19 and 20, the operation of the machine will be outlined in the manner in which it occurs when the hand lever 128 is moved to the position shown in Fig. 6. With the hand lever in this position, as has been explained above, the feed wheel 36 will be rotated in a clockwise direction, Fig. 10, so as to feed the shoe to the left as viewed in Fig. 16, while the gripper jaws 30, 32 will be oscillated by the screw 58 so as first to move to the right and then return to their mid-position in alignment with the overlaying member 34. In Fig. 16, the direction in which the shoe is fed along intermittently, by the feed wheel 36, is indicated by a solid arrow and the movements of the gripper jaws are diagrammatically illustrated by means of a relatively heavy arrowed line a, b, c, d, e, and f, that corresponds roughly to the path of movement of the inner jaw 30. Similarly, in Fig. 4, the arrowed line a, c, d, and f represents the path of movement of the inner jaw 30 in a horizontal plane, while in Figs. 17 and 18 the arrows showing the direction of movement of the gripper jaws are identified with the letters "e" and "f" corresponding to similar portions of the arrowed line "a" to "f."

It has already been pointed out above that the actions of the gripper jaws 30, 32 to seize, updraw, overdraw and release different portions of the upper materials of a shoe are the same as those of the gripper of the machine disclosed in the above-mentioned patent. The overlaying member 34 also operates in timed relation to the tensioning action of the gripper substantially in the same manner as in the patented machine. However, in the herein illustrated machine, the gripper jaws are also oscillated in a direction lengthwise of the shoe, first away from and then toward a position in line with the overlaying member and the shoe is fed along, intermittently, by means of the feed wheel in time relation to the actions of the gripper and the overlaying member.

Referring now to Figs. 3, 4, and 16-20, a complete operating cycle will be described beginning at about 240° on the timing chart (Fig. 20). At this point in the cycle, the gripper jaws 30, 32 have just tensioned and released a portion of the upper materials U and L and the lasting margin has been secured in lasted position to the inner sole I, by means of an adhesive coating previously applied to the inside surface of the upper materials and/or the insole, as a result of the pressing actions of the overlaying member 34 and the hammer 182, see Fig. 19. The hammer 182 has been elevated to a slight extent (see hammer cam on timing chart) in order not to interfere with the feeding of the shoe which begins immediately, the feed wheel 36 being rotated in a direction to move the shoe to the left in Fig. 16 (see feed cam on timing chart). During the time that the shoe is thus being moved to the left, the overlaying member 34 is withdrawn away from the shoe bottom and the gripper is swung to the right by the screw 58, so as to cause the inner jaw 30 to move along a path indicated by the line "a" (pincer side throw cam). At the conclusion of the feeding movement of the shoe and while the shoe is being held stationary by the feed wheel 36, the gripper first descends and causes the jaw 30

to move along the line "b" toward the inner sole I (updraw cam) and then moves outwardly to cause the jaw 30 to follow the path "c" (overdraw cam). Now the gripper is returned to its mid-position in alignment with the overlaying member 34, see line x-x in Fig. 4, so that the jaw 30 follows the path "d" (pincer side throw cam).

As shown in Fig. 16 by the broken lines, the lasting margin of the upper materials curves upwardly and outwardly, from the location where it has been secured to the inner sole, indicated by the dotted line representation "h" of the area acted on by the hammer in Figs. 4 and 16, to a position where it is nearly vertical to the inner sole. By moving the gripper jaws in directions lengthwise and heightwise of the shoe and causing the inner jaw 30 to follow substantially the paths a, b, c, and d, this jaw is easily inserted beneath the lasting margin of the upper materials, in a location closely adjacent to the place where the upper has been secured to the inner sole, since it first moves toward the lasting margin in a location where the margin is merely vertical and then moves in a direction lengthwise of the shoe beneath the margin. As will be apparent from an examination of the timing chart, Fig. 20, the cams are so shaped that the path a to d is only approximated and movements along the paths b, c, d occur simultaneously and more or less along the arrowed line b', c', d', Fig. 16. However, the inner jaw is inserted beneath the curved portion of the lasting margin before the gripper has returned to its mid-position and prior to operation of the gripper to seize, tension and release another portion of the upper materials.

After the gripper has been returned to its mid-position and the inner jaw inserted beneath the lasting margin in the manner explained above, the jaws 30, 32 may be closed to seize the upper materials, as shown in Fig. 17. Next, the gripper jaws are moved upwardly substantially along the path "e" to exert an updrawing stress on the upper U and lining L for tensioning these materials over the last A. Preferably, and in the herein illustrated machine, the inner jaw 30 is provided with a smooth operating face 509, for engaging the lining L, while the outer jaw 32 has a toothed operating surface 502 for engaging the upper U, and the jaws are closed on the upper materials with a relatively light pressure. Accordingly, as the jaws 30, 32 move upwardly, along the path "e," the upper and lining slip through the jaws, the tension in force applied by the smooth jaw 30 being just sufficient to remove any looseness from the lining, and the greater tensioning force exerted by the toothed jaw 32 being sufficient to stretch the upper snugly over the last A. At the conclusion of this upward movement of the jaws 30, 32, the various parts assume the positions shown in Fig. 18. Thereafter, the jaws are moved along the path "f" to draw the lasting margin inwardly over the inner sole and, at the conclusion of this overdraw movement, the jaws are opened to release the upper materials which are immediately laid in over, and pressed against, the inner sole by the actions of the operating surface 180 on the overlaying member 34 and the hammer 182.

As explained above, the overlaying member 34 is moved toward the bottom of the shoe along an inclined path, see arrows Figs. 17 and 18, and in two distinct steps with a dwell between the steps.

Referring to Figs. 17, 18 and 19, the first step of the movement of the overlaying member occurs during the beginning of the upward movement of the jaws 30, 32, in the direction of the arrow "e," Fig. 17, and the arrangement is such that movement of the overlaying member is arrested and the overlaying member held stationary while the upward movement of the jaws is completed, the overlaying member stopping with its nose 181 just touching the tension lasting margin of the upper materials as shown in Fig. 18. Now, as the jaws are moved to the left, in the direction of the arrow "f," to draw the lasting margin of the tensioned upper materials inwardly over the inner sole I, the second step of the movement of the overlaying member occurs so that the overlaying member follows the inward movement of the lasting margin and finally lays the lasting margin in over, and presses it flatly against the inner sole I, Fig. 19, with an easy and smooth action which does not jar the shoe, just after the jaws are opened (approx. 195° on the timing chart, Fig. 20). The hammer 182 is now operated to strike the lasting margin of the upper materials a sharp blow, to cause the lasting margin to be securely bonded to the inner sole by the previously applied adhesive, at about 210° on the timing chart. The cycle is completed in the next 30° during which the hammer is elevated prior to the withdrawal of the overlaying member which occurs at the beginning of the next cycle as explained above.

As suggested above, it is desirable that the gripper jaws 30, 32 operate on closely spaced portions of the upper materials to the end that these materials may be snugly stretched over the last. It is also important that all portions of the lasting margin be subjected to the action of the hammer so that every lengthwise part of the lasting margin will be securely bonded to the inner sole by the adhesive. Accordingly, the feeding increments which are imparted to the shoe by the feed wheel 36 preferably should be at least of no greater linear extent than the width of the operative face of the hammer 182. Referring to Figs. 9 and 15, the magnitude of the feeding increments may be varied by changing the position of the block 352 along the groove 355. With the parts constructed as shown, the range of feeding increments is from $\frac{1}{8}$ " to $\frac{1}{16}$ " and the block 354 is shown as so positioned as to provide for a feed of approximately $\frac{1}{4}$ ". The operating face of the hammer 182 is about $\frac{1}{2}$ " in diameter so that the areas "h" on which the hammer acts overlap slightly, as shown in Fig. 4. Preferably, and as herein illustrated, the gripper oscillating mechanism is arranged to swing the jaws 30, 32 away from their mid-position a distance that is somewhat greater than the maximum feeding movement and herein shown as being approximately $\frac{3}{8}$ ".

While feeding of the shoe by relatively short increments ($\frac{1}{4}$ ") gives improved results in that it assures that all portions of the upper materials will be subjected to lasting stress and also securely bonded to the inner sole, it also presents a problem. With a feeding increment of this magnitude, if the gripper jaws were returned all the way to their mid-position before closing, these jaws would seize a portion of the lasted margin of the upper materials in a location spaced only $\frac{1}{4}$ " away from the place where the lasting margin had been previously secured to the inner sole. As a matter of fact, the edge of the area "h," Figs. 4 and 16, which is nearer to the gripper would

be even closer to the location where the upper materials are seized by the jaws. Now, when the jaws are operated to exert an updrawal on this portion of the lasting margin, there will be a very considerable tendency for the jaws also to lift that portion of the lasting margin which had been previously secured to the inner sole.

In order to avoid this difficulty, while still retaining the advantages of the relatively short feeding increments, the following arrangement is provided. Referring to Fig. 4 and Fig. 20, the jaw cam is so shaped as to effect closing of the jaws 30, 32 on the lasting margin before the jaws have returned all the way to their mid-position. At this time in the cycle, the shoe is held stationary against movement in the direction of feed by the feed wheel 36 and the action of the spring fingers 346 (Figs. 10 and 12), so that as the jaws complete their return movement a certain amount of fullness "y" is placed in that part of the lasting margin which is between the gripper jaws and the location where the lasting margin is secured to the inner sole, see Fig. 4. Now, when the jaws are operated to updraw the upper materials, this slight fullness to a considerable extent isolates that portion of the lasting margin which has been secured to the inner sole from that portion which is being tensioned and, in this manner, prevents the former from being lifted up or otherwise disturbed. It has been found that a very slight amount of fullness is quite effective, in this respect, and, in fact, if the jaws are closed in a location only $\frac{1}{16}$ " to $\frac{1}{8}$ " away from mid-position, as shown on the timing chart, all difficulties with regard to a disturbance of previously secured portions of the lasting margin is avoided. At the same time, such a small amount of fullness is not enough to cause any undesirable pleating of the lasting margin on the shoe bottom or distortion of the upper on the last. Actually, this gathering-in of the upper material, in the direction of feed, results in a better lasting action. With the updraw and pincer side throw cams shaped, as illustrated on the timing chart, Fig. 20, the updraw movement of the gripper begins while the gripper is returning to its mid-position. However, no actual tension is applied to the upper materials until the gripper jaws have returned to mid-position and the aforementioned fullness placed in the lasting margin of the upper materials.

In lasting a shoe, it is a usual practice for the operator to start the lasting operation at the breast line, on one side of the shoe, and then to proceed to the tip line. After one side of the shoe has been lasted, the shoe is turned around to bring its other side to the machine and the lasting operation repeated, again beginning at the breast line and proceeding to the tip line. Obviously, such a procedure requires that the shoe be fed along from right to left, on one side, and from left to right on the other side. In the herein illustrated machine, the direction of feed may be reversed by manipulating the hand lever 128 which also changes the direction in which the gripper jaws 30, 32 are moved away from their mid-position. The dotted arrow on the shoe and the relatively light arrowed line "a" to "d" in Fig. 16 indicate the direction of feed and the path of movement of the gripper when the hand lever 128 is moved to the position shown in dotted line in Fig. 6 and in solid line in Fig. 1. It will be understood that the portions "e" and "f" of the path of movement of the inner jaw 30 will be the same, and lie in a plane that is in alignment with the

overlaying member 34, regardless of the position of the hand lever 128.

As suggested above, the operation of the main shaft 44 is under the control of two treadle rods 43 and 48. In the same manner as in the prior patented machine, these treadle rods are arranged to be operated by two treadles, not shown, in such a manner that both rods may be moved downwardly to effect operation of the gripper, feed wheel and overlaying member, or the rod 43 only may be moved downwardly to effect operation of the overlaying member and feed wheel, while the gripper remains idle. In either case, the clutch mechanisms are adapted to present the main shaft to a stop with the gripper jaws opened and the overlaying member withdrawn, as shown in Fig. 3. Also, the feed wheel 36 may be disconnected from its driving means should the operator wish to feed the shoe manually. Under these conditions, the hand lever 128 may still be manipulated to control the widthwise movement of the gripper jaws in accordance with the direction in which the operator desires to feed the shoe.

Having described our invention, what we claim as new and desire to protect by United States Letters Patent is:

1. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating said gripper lengthwise of the shoe, away from and then toward a position in line with the overlaying member, after the gripper has tensioned and released a portion of the upper, said gripper-operating mechanism and said gripper-oscillating mechanism being so relatively timed as to cause the gripper to be returned substantially to a position in line with the overlaying member prior to tensioning another portion of the upper.

2. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating said gripper lengthwise of the shoe, selectively, in either direction, away from and then toward a position in line with the overlaying member, after the gripper has tensioned and released a portion of the upper, said gripper-operating mechanism and said gripper oscillating mechanism being so relatively timed as to cause the gripper to be returned substantially to a position in line with the overlaying member prior to tensioning another portion of the upper.

3. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating said gripper lengthwise of the shoe,

away from and then toward a position in line with the overlaying member, after the gripper has tensioned and released a portion of the upper, said gripper-operating mechanism and said gripper-oscillating mechanism being so relatively timed as to cause the gripper as it is moved toward the overlaying member to seize another portion of the upper and to displace said portion in a direction lengthwise of the shoe and into alignment with the overlaying member, prior to operation of the gripper for tensioning said other portion of the upper.

4. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating said gripper lengthwise of the shoe, selectively, in either direction, away from and then toward a position in line with the overlaying member, after the gripper has tensioned and released a portion of the upper, said gripper-operating mechanism and said gripper-oscillating mechanism being so relatively timed as to cause the gripper as it is moved toward the overlaying member to seize another portion of the upper and to displace said portion in a direction lengthwise of the shoe and into alignment with the overlaying member, prior to operation of the gripper for tensioning said other portion of the upper.

5. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating the gripper lengthwise of the shoe, away from and then toward a position in line with the overlaying member, after the gripper has tensioned and released a portion of the upper, said gripper-operating mechanism and said gripper-oscillating mechanism being so relatively timed as to cause the gripper as it is moved toward the overlaying member to seize another portion of the upper and to displace said portion in a direction lengthwise of the shoe and into alignment with the overlaying member, prior to operation of the gripper for tensioning said other portion of the upper.

6. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating the gripper lengthwise of the shoe, selectively, in either direction, away from and then toward a position in line with the overlaying member, after the gripper has tensioned and released a portion of the upper and prior to operation of the gripper to tension another portion of the upper, said gripper-operating mechanism being also arranged to move the gripper laterally of the shoe, in time relation to the action of said gripper-oscillating mechanism, so as to cause the inner jaw of the gripper as it is moved toward the overlaying member to be inserted beneath the lasting margin of the upper closely adjacent to the location where said margin has been laid over, and pressed against, the shoe bottom.

erating mechanism being also arranged to move the gripper laterally of the shoe, in time relation to the action of said gripper-oscillating mechanism, so as to cause the inner jaw of the gripper, as it is moved toward the overlaying member, to be inserted beneath the lasting margin of the upper closely adjacent to the location where said margin has been laid over, and pressed against, the shoe bottom.

7. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating the gripper lengthwise of the shoe away from and then toward a position in line with the overlaying member, after the gripper has tensioned and released a portion of the upper and prior to operation of the gripper to tension another portion of the upper, said gripper-operating mechanism also being arranged to move the gripper downwardly and laterally of the shoe, in time relation to the action of said gripper-oscillating mechanism, so as to cause the inner jaw of the gripper as it is moved toward the overlaying member to be inserted beneath the lasting margin of the upper closely adjacent to the location where said margin has been laid over, and pressed against, the shoe bottom.

8. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating the gripper lengthwise of the shoe, selectively, in either direction, away from and then toward a position in line with the overlaying member, after the gripper has tensioned and released a portion of the upper and prior to operation of the gripper to tension another portion of the upper, said gripper-operating mechanism also being arranged to move the gripper downwardly and laterally of the shoe, in time relation to the actions of said gripper-operating mechanism, so as to cause the inner jaw of the gripper as it is moved toward the overlaying member to be inserted beneath the lasting margin of the upper closely adjacent to the location where said margin has been laid over, and pressed against, the shoe bottom.

9. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, and mechanism for oscillating the gripper lengthwise of the shoe, away from and then toward a position in line with the overlaying member, after the gripper has tensioned and released a portion of the upper, said gripper-operating mechanism also being arranged to move the gripper downwardly toward the shoe bottom and laterally to-

ward the edge of the shoe, in time relation to the action of said gripper-oscillating mechanism, so as to cause the inner jaw of the gripper as it is moved toward the overlaying member to be inserted beneath the lasting margin of the upper closely adjacent to the location where said margin has been laid over, and pressed against the shoe bottom, and said gripper-operating mechanism and said gripper-oscillating mechanism being so relatively timed as to cause the gripper to be returned substantially to a position in line with the overlaying means prior to tensioning another portion of the upper.

10. A lasting machine having, in combination, a gripper and mechanism for operating the gripper to seize, tension and release portions of the upper of a shoe, successively, in different locations along the edge of the shoe bottom, an overlaying member operable, in time relation to the actions of said gripper, to lay the lasting margin of the tensioned upper in over, and to press it against, the shoe bottom in each location, the mechanism for oscillating the gripper lengthwise of the shoe, selectively, in either direction away from and then toward a position in line with the overlaying member, after the gripper has tensioned and released a portion of the upper, said gripper-operating mechanism being also arranged to move the gripper downwardly toward the shoe bottom and laterally toward the edge of the shoe, in time relation to the action of said gripper-oscillating mechanism, so as to cause the inner jaw of the gripper, as it is moved toward the overlaying member, to be inserted beneath the lasting margin of the upper closely adjacent to the location where said margin has been laid over, and pressed against, the shoe bottom, and said gripper-operating mechanism and said gripper-oscillating mechanism being so relatively timed as to cause the gripper to be returned substantially to a position in line with the overlaying member prior to tensioning another portion of the upper.

11. A lasting machine having, in combination, a gripper and mechanism for operating the gripper to seize, tension and release a portion of the upper of a shoe, an overlaying member operable in time relation to the action of the gripper, to lay the lasting margin of the tensioned upper in over, and to press it against, the bottom of the shoe, means for feeding the shoe intermittently to present different portions of the upper, successively, to the actions of the gripper and the overlaying member, and mechanism for oscillating said gripper lengthwise of the shoe, away from and then toward a position in line with the overlaying member, after the gripper has tensioned and released a portion of the upper, said gripper-operating mechanism and said gripper-oscillating mechanism being so relatively timed as to cause the gripper to be returned substantially to a position in line with the overlaying member prior to tensioning another portion of the upper and said feeding means being adapted to feed the shoe, in the opposite direction, when the gripper is moving away from the overlaying member and to hold the shoe against movement in the direction of feed when said gripper is moving toward the overlaying member.

12. A lasting machine having, in combination, a gripper and mechanism for operating the gripper to seize, tension and release a portion of the upper of a shoe, an overlaying member operable in time relation to the action of the gripper, to lay the lasting margin of the tensioned upper in

over, and to press it against, the bottom of the shoe, means for selectively feeding the shoe, in either direction, intermittently to present different portions of the upper, successively, to the actions of the gripper and the overlaying member, and mechanism for oscillating said gripper lengthwise of the shoe, selectively, in either direction away from and then toward a position in line with the overlaying member, after the gripper has tensioned and released a portion of the upper, said gripper-operating mechanism and said gripper-oscillating mechanism being so relatively timed as to cause the gripper to be returned substantially to a position in line with the overlaying member prior to tensioning another portion of the upper and said feeding means being adapted to feed the shoe, in the opposite direction, when the gripper is moving away from the overlaying member and to hold the shoe against movement in the direction of feed when said gripper is moving toward the overlaying member.

13. A lasting machine having, in combination, a gripper and mechanism for operating the gripper to seize, tension and release a portion of the upper of a shoe, an overlaying member operable in time relation to the action of the gripper, to lay the lasting margin of the tensioned upper in over, and to press it against, the bottom of the shoe, means for feeding the shoe intermittently to present different portions of the upper, successively, to the actions of the gripper and the overlaying member, and mechanism for oscillating said gripper lengthwise of the shoe, away from and then toward a position in line with the overlaying member, after the gripper has tensioned and released a portion of the upper, said gripper-operating mechanism and said gripper-oscillating mechanism being so relatively timed as to cause the gripper as it is moved toward the overlaying member to seize another portion of the upper and to displace it in a direction lengthwise of the shoe and into alignment with said overlaying member, prior to the operation of the gripper for tensioning said other portion of the upper and said feeding means being adapted to feed the shoe, in the opposite direction, when the gripper is moving away from the overlaying member and to hold the shoe against movement in the direction of feed when the gripper is moving toward the overlaying member and is displacing said portion of the upper.

14. A lasting machine having, in combination, a gripper and mechanism for operating the gripper to seize, tension and release a portion of the upper of a shoe, an overlaying member operable in time relation to the action of the gripper, to lay the lasting margin of the tensioned upper in over, and to press it against, the bottom of the shoe, means for selectively feeding the shoe, in either direction, intermittently to present different portions of the upper, successively, to the actions of the gripper and the overlaying member, and mechanism for oscillating said gripper lengthwise of the shoe, selectively, in either direction away from and then toward a position in line with the overlaying member, after the gripper has tensioned and released a portion of the upper, said gripper-operating mechanism and said gripper-oscillating mechanism being so relatively timed as to cause the gripper as it is moved toward the overlaying member to seize another portion of the upper and to space it in a direction lengthwise of the shoe, and into alignment with said overlaying member, prior to operation of the gripper for tensioning said other portion of the upper

and said feeding means being adapted to feed the shoe, in the other direction, when the gripper is moving away from the overlaying member and to hold the shoe against movement in the direction of feed when the gripper is moving toward the overlaying member and is displacing said portion of the upper.

15. A lasting machine having, in combination, a gripper and mechanism for operating the gripper to seize, tension and release a portion of the upper of a shoe, an overlaying member operable in timed relation to the action of the gripper to lay the lasting margin of the tensioned upper in over, and press it against the bottom of the shoe, means for feeding the shoe intermittently to present different portions of the upper, successively to the actions of the gripper and the overlaying member, and mechanism for oscillating the gripper lengthwise of the shoe, away from and then toward a position in line with the overlaying member, after the gripper has tensioned and released a portion of the upper, said gripper operating mechanism being also arranged to move the gripper laterally of the shoe, in time relation to the action of the gripper oscillating mechanism, so as to cause the inner jaw of the gripper as it is moved toward the overlaying member to be inserted beneath the lasting margin of the upper closely adjacent to the location where said margin has been laid over, and pressed against, the shoe bottom and said feeding means being adapted to feed the shoe, in the opposite direction, when the gripper is moving away from the overlaying member and to hold the shoe against movement in the direction of feed when the gripper is moving toward the overlaying member.

16. A lasting machine having, in combination, a gripper and mechanism for operating the gripper to seize, tension and release a portion of the upper of a shoe, an overlaying member operable in timed relation to the action of the gripper to lay the lasting margin of the tensioned upper in over, and to press it against, the bottom of the shoe, means for selectively feeding the shoe, in either direction, intermittently to present different portions of the upper, successively to the actions of the gripper and the overlaying member, and mechanism for oscillating the gripper lengthwise of the shoe, selectively, in either direction away from and then toward a position in line with the overlaying member, after the gripper has tensioned and released a portion of the upper, said gripper operating mechanism being also arranged to move the gripper laterally of the shoe, in time relation to the action of said gripper oscillating mechanism, so as to cause the inner jaw of the gripper as it is moved toward the overlaying member to be inserted beneath the lasting margin of the upper closely adjacent to the location where said margin has been laid over, and pressed against, the shoe bottom and said feeding means being adapted to feed the shoe in the opposite direction, when the gripper is moving away from the overlaying member and to hold the shoe against movement in the direction of feed when the gripper is moving toward the overlaying member.

17. A lasting machine having, in combination, a gripper mechanism for operating the gripper to seize, tension and release a portion of the upper of a shoe, an overlaying member operable in timed relation to the action of the gripper, to lay the lasting margin of the tensioned upper in over, and to press it against, the bottom of the shoe, means for feeding the shoe intermittently

21

to present different portions of the upper, successively, to the actions of the gripper and the overlaying member, and mechanism for oscillating the gripper lengthwise of the shoe, away from and then toward a position in line with the overlaying member, after the gripper has tensioned and released a portion of the upper, said gripper operating mechanism being also arranged to move the gripper downwardly toward the shoe bottom and laterally toward the edge of the shoe, in time relation to the action of the gripper operating mechanism, so as to cause the inner jaw of the gripper as it is moved toward the overlaying member to be inserted beneath the lasting margin of the upper closely adjacent to the location where said margin has been laid over, and pressed against the shoe bottom, and said gripper operating mechanism and said gripper oscillating mechanism being so relatively timed as to cause the gripper to be returned substantially to a position in line with the overlaying means prior to tensioning another portion of the upper, and said feeding means being adapted to feed the shoe, in the opposite direction, when the gripper is moving away from the overlaying member and to hold the shoe against movement in the direction of feed when the gripper is moving toward the overlaying member.

18. A lasting machine having, in combination, a gripper and mechanism for operating the gripper to seize, tension and release a portion of the upper of a shoe, an overlaying member operable in timed relation to the action of the gripper to lay the lasting margin of the tensioned upper in over, and to press it against, the bottom of the shoe, means for selectively feeding the shoe, in either direction, intermittently to present different portions of the upper, successively, to the actions of the gripper and the overlaying member, and mechanism for oscillating said gripper lengthwise of the shoe, selectively, in either direction, away from and then toward a position in line with the overlaying member, after the gripper has tensioned and released a portion of the upper, said gripper operating mechanism being also arranged to move the gripper downwardly toward the bottom of the shoe and laterally toward the edge of the shoe, in timed relation to the action of said gripper oscillating mechanism, so as to cause the inner jaw of the gripper as it is moved toward the overlaying member to be inserted beneath the lasting margin of the upper closely adjacent to the location where said margin has been laid over, and pressed against, the shoe bottom, said gripper operating mechanism and said gripper oscillating mechanism being so relatively timed as to cause the gripper to be returned substantially to a position in line with the overlaying member prior to tensioning another portion of the upper and said feeding means being adapted to feed the shoe, in the opposite direction when the gripper is moving away from the overlaying member and to hold the shoe against movement in the direction of feed when the gripper is moving toward the overlaying member.

19. A lasting machine having, in combination, a gripper for seizing, tensioning and releasing portions of the upper of a shoe, successively, in different locations along the edge of the shoe bottom, an overlaying member and mechanism for operating the overlaying member, in time relation to the action of said gripper, to lay the lasting margin of the tensioned upper in over, and to press it against, the bottom of the shoe in

22

each location, said overlaying member being arranged to move along a path inclined downwardly toward the bottom of the shoe and having an operating face disposed at an angle to said path and substantially parallel to the plane of the bottom of the shoe and said operating mechanism being adapted to cause the overlaying member first to move toward the shoe bottom during a portion of the tensioning action of the gripper, then to pause while the tensioning action is completed, and finally to lay the lasting margin in over, and to press it against, the bottom of the shoe as the upper is released by the gripper.

20. A lasting machine having, in combination, a gripper for seizing, updrawing, overdrawing and then releasing portions of the upper of a shoe, successively, in different locations along the edge of the shoe bottom, an overlaying member, and mechanism for operating the overlaying member, in time relation to the action of said gripper, to lay the lasting margin of the tensioned upper in over, and to press it against, the bottom of the shoe in each location, said operating mechanism being adapted to cause the overlaying member first to move toward the shoe bottom, during a portion of the updraw, next to pause while the updraw is completed, then to continue movement toward the shoe bottom during the overdraw and finally to lay the lasting margin in over, and to press it against, the bottom of the shoe as the upper is released by the gripper.

21. A lasting machine having, in combination, a gripper for seizing, updrawing, overdrawing and then releasing portions of the upper of a shoe, successively, in different locations along the edge of the shoe bottom, an overlaying member and mechanism for operating the overlaying member, in time relation to the actions of said gripper, to lay the lasting margin of the tensioned upper in over, and to press it against, the bottom of the shoe in each location, said overlaying member being arranged to move along a path inclined downwardly toward the bottom of the shoe and having an operating face disposed at an angle to said path and substantially parallel to the plane of the bottom of the shoe and said operating mechanism being adapted to cause the overlaying member first to move toward the shoe bottom, during a portion of the updraw, next to pause while the updraw is completed, then to continue movement toward the shoe bottom during the overdraw and finally to lay the lasting margin in over, and to press it against, the bottom of the shoe as the upper is released by the gripper.

22. A lasting machine having, in combination, means for tensioning portions of the upper of a shoe, successively, in different locations along the edge of the shoe bottom, an overlaying member operating, in time relation to said tensioning means, to lay the lasting margin of the tensioned upper in over, and to press it against, the bottom of the shoe in each location, and a hammer carried by the overlaying member and adapted to strike the lasting margin a sharp blow, after said lasting margin has been pressed against the shoe bottom by the overlaying member, said hammer being mounted for universal movement about axes extending widthwise and lengthwise of the shoe bottom so as to strike said lasting margin squarely and evenly regardless of lengthwise and widthwise curvatures of the shoe bottom.

23. A lasting machine having, in combination, means for tensioning portions of the upper of a shoe, successively, in different locations along the

edge of the shoe bottom, an overlaying member movable toward the shoe bottom, in time relation to the action of said tensioning means, for laying the lasting margin of the tensioned upper in over, and for pressing it against, the bottom of the shoe in each location, said overlaying member being arranged to move along a path that is inclined downwardly toward the shoe bottom and having an operating surface disposed at an angle to said path and substantially parallel to the plane of the shoe bottom, and a self-leveling hammer carried by the overlaying member and adapted to be projected through an opening in said operating surface and against the lasting margin after said margin has been pressed 15 against the shoe bottom by the overlaying member.

24. A lasting machine having, in combination, means for tensioning portions of the upper of a shoe, successively, in different locations along the edge of the shoe bottom, a member operating in time relation to the action of said tensioning means for pressing a narrow area of the upper against the bottom of the shoe in each location, and means for selectively feeding the shoe, in either direction, intermittently to present different portions of the upper to the actions of the tensioning means and the pressing member, said feeding means being constructed and arranged

to impart feeding movements to the shoe, in either direction, of a linear extent less than the width of the areas acted on by the pressing means.

25. A lasting machine having, in combination, means for tensioning portions of the upper of a shoe, successively, in different locations along the edge of the shoe bottom, a hammer operating in time relation to the action of said tensioning means for applying a blow to a narrow area of the upper in each location, and means for selectively feeding the shoe, in either direction, intermittently to present different portions of the upper to the actions of the tensioning means and the hammer, said feeding means being constructed and arranged to impart feeding movements to the shoe of a linear extent less than the width of the areas acted on by the hammer.
